PEBBLE HEATER DESIGN

Russell K. Simms, Bartlesville, Okla., assignor to
Phillips Petroleum Company, a corporation of
Delaware

Application December 5, 1947, Serial No. 789,805

7 Claims. (Cl. 196—55)

1

This invention pertains to a process and apparatus for effecting chemical reactions at elevated temperatures in the vapor phase. A specific aspect of the invention relates to the conversion of hydrocarbons.

In various chemical processes the character of the reaction product is dependent upon the specific reaction time utilized, especially at elevated temperatures. In such processes performed in a reactor, either packed with a stationary contact bed or in which a moving contact bed continuously passes through the reaction chamber, there is a substantial vapor space above the contact mass in which the reaction products are given a substantial soaking period which may result in undesirable side reactions between the vaporous constituents or in decomposition of the desired reaction product. For example, in the cracking of hydrocarbons for the production of olefins, it is essential to high yields of the olefin to remove the olefin-rich cracked vapors from the high temperature vapor space above the contact bed in the shortest possible time in order to avoid overcracking with excessive deposition of carbon on the walls of the vapor space.

In the typical pebble heater design, a pebble throat introduces hot pebbles to the conversion chamber at a point a substantial distance below the upper end of the conversion chamber in order to provide a gas collecting space above the pebble bed. In hydrocarbon cracking processes, considerable difficulty is experienced, not only in over-cracking of the feed stock in this free space above the pebble bed, but also in excessive deposition of carbon around the pebble throat. Factors contributing to the difficulty are the extremely high temperature of the throat through which the hottest pebbles are passing and eddy currents or stagnant areas in the vapor space where the gases are subjected to soaking and complete breakdown to carbon. In many hydrocarbon cracking processes conducted in a pebble heater unit, the cracked, olefin-rich gases flowing from the pebble bed to the product gas outlet are at a temperature of upwards of 1600° F. Due to the shape of the vapor space and the presence of the pebble inlet throat, effluent vapors from the pebble bed swirl around this area before passing through the outlet, thus prolonging cracking time and reducing yield of olefin as well as increasing carbon deposition. A plurality of outlets improves the situation, but does not effect a complete solution to the problem. It is with the streamlining of the gas flow through the free

2

space above the contact mass in a conversion chamber and with the reduction in carbon deposition on the walls and throat of the reactor in this space that this invention is concerned.

5 An important object of the present invention is to provide an improved reactor which reduces the residence time of the reaction products in the free space in the reactor. Another object is to streamline the flow of reaction products out 10 of the reaction chamber. It is also an object of this invention to eliminate stagnant areas and eddy currents with concomitant reduction of carbon deposition in the free space above the contact mass in a reactor. Another object is to 15 protect the throat of a pebble heater reactor from excessive carbon deposition. Still another object is to increase the yield of the desired product in certain hydrocarbon conversion reactions. Other objects of the invention will be 20 come apparent from the accompanying disclosure.

My invention provides for streamlining the flow of gases through the free space above a contact mass or pebble bed in a reaction chamber by restricting the cross-sectional area of the space 25 through which the reaction products flow by the use of baffles shaped to direct the flow into a plurality of outlets through the top of the reaction chamber. By progressively reducing the effective cross-sectional area of the vapor space 30 between the contact bed and the vapor outlets, the flow rate of the gaseous product is increased proportionally, thereby reducing the residence time of the reaction products in the reactor and making it possible to quench the same to below 35 reaction temperatures in the shortest possible time.

In order to more fully explain and illustrate the features and advantages of the invention, reference is made to the accompanying diagrammatic drawing and the following description thereof.

Figure 1 is a cross-section taken on the line 1—1 of Figure 2 showing the upper portion of a reactor according to one embodiment of the invention.

Figure 2 is a top plan view of the reactor with the right half of the top closure member removed.

Figure 3 is a perspective view of the reactor with the top closure member removed along the line 3—3 of Figure 1 and with the shell removed.

Figure 4 is a plan view showing the arrangement of apparatus in a typical pebble heater unit including a reactor of the type to which the invention applies.

Referring now to the drawing, the reactor is

made up of an outer cylindrical shell 11 enclosing a refractory lining 12 which may be made of conventional furnace refractories along with less expensive insulating materials and may consist of several layers with the more expensive refractory in the innermost layer. A top closure member 13 has the same construction as the cylindrical shell, being lined with refractory material 11 and attached to the cylindrical shell by means of flanged members 14. Top closure member 13 is pierced by pebble inlet conduit 15 and a series of symmetrically arranged product outlet conduits 16. A refractory arched baffle 17 converges in cooperation with the walls of the reactor to form a funnel-shaped passageway to each of the product outlets. A ring member 18 suitably attached to pebble inlet conduit 15 near its lower end assists in supporting the baffles. Numeral 19 represents a bed of pebbles or particulate contact material introduced through pebble inlet 15.

Figure 2 shows an arrangement of four product outlets symmetrically arranged around an axially positioned pebble inlet. This figure shows supporting arches 20 for adjacent walls of arched funnels or baffles 17. The invention is not limited to the particular arrangement or number of product outlets or pebble inlets shown. It is feasible to use a plurality of pebble inlets along with a plurality of product outlets. Obviously, a symmetrical arrangement of the product outlets enhances the uniformity of gas flow and is advantageous although not absolutely necessary to the reactor design. The invention also encompasses an arrangement of two, three, and any reasonable number above four, product outlets arranged around the pebble inlet.

Figure 3 offers a clearer picture of the funnel-shaped baffles which serve to streamline and funnel the flow of product gas out of the reactor. The invention is not limited to the particular shape of baffles shown in the drawing although this is a preferred modification of the invention. Any curved and arched baffle which reduces the effective cross-sectional area across the free vapor space above the contact bed and streamlines and funnels the flow of product gas to the product gas outlets, resulting in more rapid removal of product gas from the vapor space above the contact bed, is within the scope of the invention.

Figure 4 shows a conventional arrangement of pebble heater apparatus including a pebble heating chamber 21 and a reaction chamber 22 connected by a pebble throat 15 which serves as a pebble inlet to the reactor. A pebble outlet 23 connects to a suitable elevator 24 by means of a chute 25. A chute 26 connects the delivery end of the elevator to a pebble inlet 27 entering heater 21. Hot combustion gas or a combustible mixture of air and fuel is admitted to heating chamber 21 through inlet 29 and combustion gas exhausts through stack 31 heating the pebbles to a desired temperature by direct contact therewith in passing through the chamber. Any desirable feed is admitted to the reactor through line 32, passes upwardly through the hot pebble bed and exhausts through outlets 16. In pebble heater operation, a continuous mass of pebbles is circulated through the heater and reactor, absorbing heat in the heater and imparting heat to the feed gas in the reactor to heat up the reactants and furnish the heat of reaction required in the specific process being performed.

While it is preferable to use pebbles and pebble heater technique in the invention, any fluent

mass of contact material can be used. The pebbles or contact material may be either catalytic or noncatalytic with respect to the particular process being performed. The term "pebble" as used in the art, designates a particulate, refractory, heat-transfer material of fluent form and size, but is usually substantially spherical and ranges in size from about $\frac{1}{8}$ inch to 1 inch.

Baffles 17 may be fabricated in a variety of ways. In many instances, it may be desirable to construct the reactor as shown in Figure 1 with flanged means for attaching the head or top closure member to the cylindrical side wall as shown in the figure. In numerous applications of the invention, the operating conditions will be such that the baffles can be advantageously constructed from alloy steels such as 25-20 chrome nickel steel. This is feasible where operating temperatures do not exceed about 2000° F. and where reactions involved are not deleteriously catalyzed by the metal. When the arched baffles are formed from such alloys, they may be hung or suspended from the dome of the reactor by conventional means and may be perfectly streamlined funnels, the upper end of which is attached directly to the outlet conduits by welding or flanging.

Under temperatures much above 2000° F. and where it is desirable to carry on the particular reaction or conversion without contact with a metal surface, the baffles may be constructed by forming them from an alloy steel with a refractory lining. In this case, the steel baffles are fabricated with lugs or spines, or the equivalent thereof, on the inner surface. These projections from the inner surface serve as the attaching or retaining means for a refractory lining. Such a lining is conveniently formed from silimanite which comprises aluminum and silicon oxides. This material may be mixed with water and applied as a sort of plaster to the alloy as the inner surface of the baffle. Upon setting of the mix and proper heat treatment thereof, a refractory lining is produced. Other insulating and refractory materials may be applied in the same or other conventional manner. In some instances, it is desirable to apply a coating of cheaper insulating material to the baffle followed by a coating of more refractory material.

Another method of fabrication involves the use of super refractory brick or tile shapes. These bricks may be formed from conventional high temperature refractories such as those comprising aluminum oxide, magnesium oxide, thorium oxide, zirconium oxide, silicon carbide, etc., which are sold commercially under various trade names. In this type of construction, it is necessary to "lay up" or build the arched baffles into the refractory wall of the reactor. The baffles are not supported by suspension from the top of the reactor or the outlet conduits, but are supported at the base by the walls of the reactor. A supporting ring of "skew blocks" is built into the reactor lining in such a manner as to support the built up refractory baffles. In order to support the bottom edge of the baffles which terminate in the free space of the reactor, it is usually necessary to construct a refractory arch which is self-supporting and also capable of supporting the additional weight of the baffles or funnels. The outer edge of the arch is sprung from the skew blocks and the inner end wedges against the pebble throat or inlet. These sprung arches 20 in Figures 1 and 2, provide support under the

lower adjacent edges of the baffles as shown in the drawing.

When the baffles are built up from refractory tile shapes or bricks, it is usually not practical to provide and lay tiles or bricks which will seal between the upper terminals of the baffles and the reactor head or outlet conduits. It is usually more practical to use a flange on the reactor head and to insulate this head with castable or plastic refractory just prior to placing it on the reactor. The plastic refractory thus seals around and against the refractory baffle. The reactor head may also be insulated by making a template thereof which also incorporates the upper terminals of the funnel shaped baffles making a negative of this template and casting the refractory head therefrom. An additional construction modification involves the use of wooden or light metal forms which are then filled with a refractory mix or a rammed refractory material. In this way, the funnel shaped baffles are cast or formed in place and supported by skew blocks built into the reactor walls.

In some installations, it may be desirable to fill in with insulating material the void space blocked off by the baffle funnels 17 and pebble inlet 15. In installations where heat loss is not an important factor, it may be advantageous to fabricate the reactor head or top closure member with ventilating holes or slots leading into the void space between the refractory funnels and the pebble throat or inlet. This type of construction will help to cool the throat wall and makes higher pebble temperatures possible with a given refractory material.

Example

Component	Feed		Cracked Prods., Wt. percent
	Mol per- cent	Wt. per- cent	
H ₂			3.06
CH ₄	19.0	10.4	16.74
C ₂ H ₂			1.15
C ₂ H ₄			42.14
C ₂ H ₆	67.5	69.3	25.11
C ₃ H ₆			0.24
C ₃ H ₈			3.49
C ₄ H ₈	13.5	20.3	4.35
C ₄ H ₁₀			1.94
C ₅			0.83
C ₆ and heavier			0.95
	100.0	100.0	100.00
Temperature, F.			1,800°
Pressure, Atm. abs.			1
Time, sec.			0.014
Percent C ₂ H ₆ reacted			80.0
Percent C ₂ H ₄ reacted			64.3

The foregoing example illustrates the utility of the invention in a specific application. A light paraffinic stream of the composition given taken from a fractionation plant is cracked in apparatus in accordance with the invention to produce an effluent of the composition set forth. The extremely short reaction time of .014 second is indicative of the manner in which the invention operates to effect high yield of olefins with relatively low conversion to hydrogen, methane, and heavier paraffins.

Numerous modifications of the invention may be made within the scope thereof which is limited only by the appended claims.

I claim:

1. A pebble heater reactor comprising in combination a substantially vertically disposed cylindrical walled chamber having a crowned top closure member, an axially disposed tubular inlet

for pebbles extending a substantial distance through said closure member into the interior of said chamber, a plurality of reaction product outlets symmetrically disposed around aforesaid inlet, baffle means for each of said outlets extending from the proximity of the interior end of aforesaid tubular inlet and in contact therewith upwardly and laterally thereof to define an essentially funnel-shaped zone communicating at its apex with said outlet so as to streamline and funnel the flow of said reaction products through said zone without contacting said tubular inlet, inlet means in the lower portion of said reactor for introducing reactant gas, and outlet means in the lower portion of said reactor for withdrawing pebbles.

2. A pebble heater reactor comprising in combination a substantially vertically disposed cylindrical walled chamber having a crowned top closure member, an axially disposed tubular inlet for pebbles extending a substantial distance through said closure member into the interior of said chamber, a plurality of spaced apart openings through said closure member for withdrawing reaction products from the reactor, a plurality of essentially funnel-shaped chambers in communication at their apexes with said openings, said chambers being bounded by baffles extending from the proximity of the interior end of said tubular inlet curvilinearly upwardly and laterally to a juncture with the walls of said walled chamber so as to streamline and funnel the flow of said reaction products from said reactor, inlet means in the lower portion of said reactor for introducing reactant gas, and outlet means in the lower portion of said reactor for withdrawing pebbles.

3. The apparatus of claim 2 further characterized in that said baffles substantially completely surround and shield the lateral surface of that portion of said tubular inlet extending into said reactor.

4. In a process for effecting thermal conversions in the vapor phase at elevated temperatures comprising introducing a suitable feed gas into the lower portion of a descending bed of hot contact material being introduced into a conversion zone through a contact material inlet protruding downwardly from the upper end of said conversion zone in such manner as to form a substantial space between the upper surface of said bed and the upper end of said conversion zone, removing contact material from the lower portion of said conversion zone, and flowing conversion products from the upper end of said conversion zone; wherein desired conversion products suffer degradation upon continued residence time in said space; the improvement comprising funneling the flow of conversion products out of contact with said inlet through said space in a plurality of zones of progressively restricted cross-section in the direction of flow thereof, thereby decreasing the residence time of said conversion products in said space.

5. The process of claim 4 further characterized in that the feed gas comprises a hydrocarbon.

6. In a process for cracking hydrocarbons at elevated temperatures in the vapor phase comprising introducing a suitable hydrocarbon feed into the lower portion of a descending bed of hot contact material being introduced into a cracking zone through a contact-material inlet means extending downwardly into said zone so as to form a substantial space between the upper surface of said bed and the upper end of said crack-

ing zone, removing contact material from the lower portion of said cracking zone, and flowing reaction products from the upper end of the cracking zone; wherein desired products of the reaction suffer degradation upon continued residence time in said space with concomitant deposition of carbonaceous material on said inlet means; the improvement comprising streamlining and funneling the flow of reaction products out of contact with said inlet means upwardly through said space in a plurality of zones of progressively restricted cross-section in the direction of flow, thereby decreasing the residence time of said reaction products in said space and avoiding carbon deposition on said inlet means.

7. A reactor comprising in combination a vertical cylindrical shell having end closure members and a refractory lining enclosing a reaction chamber; inlet means in the lower portion of said chamber for introducing gaseous reactant thereto; an axially disposed tubular pebble inlet extending downwardly into the upper section of said chamber so as to form a vapor collecting space in the upper end of said chamber when

10
15

pebbles are admitted thru said inlet; a plurality of symmetrically disposed openings in the top closure member for withdrawing gases from said chamber; a plurality of tapered refractory baffles each forming an upwardly converging gas collecting zone communicating through its upper and smaller end with one of said openings, the lower and flared ends of said baffles occupying the inner horizontal cross-sectional area of said chamber exclusive of said pebble inlet in a symmetrical pattern around said pebble inlet; and pebble outlet means in the bottom closure member for withdrawing pebbles from said chamber.
